UNITED STATES PATENT OFFICE

171,312

ELECTRIC VAPORIZER

Joy B. Schmitt, Somerset, Pa., and Alvin J. Attinger, Toledo, Ohio, assignors to The DeVilbiss Company, Toledo, Ohio, a corporation of Ohio

Application May 20, 1953, Serial No. 25,118

Term of patent 14 years

(Cl. D83—1)

To all whom it may concern:

Be it known that we, Joy B. Schmitt and Alvin J. Attinger, respectively, a citizen of the United States, residing at Somerset, county of Somerset, State of Pennsylvania, and a citizen of the United States, residing at Toledo, county of Lucas, State of Ohio, have invented a new, original, and ornamental Design for an Electric Vaporizer, of which the following is a specification, reference being had to the accompanying drawings, forming part thereof.

In the drawings:

Fig. 1 is a front elevational view of an electric vaporizer, showing our new design;

Fig. 2 is a plan view thereof; and

Fig. 3 is a fragmentary rear elevation of the top portion only of the vaporizer of Figs. 1 and 2.

The characteristic features of our design reside in the top portions having the configuration shown.

We claim:

The ornamental design for an electric vaporizer, as shown and described.

JOY B. SCHMITT,
ALVIN J. ATTINGER.
